FIG. I

FIG. 2

Inventor:

Jean Olivier de Chappes de lairine

UNITED STATES PATENT OFFICE

2,416,471

WATER SPORT DEVICE

Jean Olivier de Chappedelaine, Reading, Pa.

Application August 15, 1944, Serial No. 549,585

2 Claims. (Cl. 9—18)

1

My invention relates to an apparatus actuated by hands and which can be used in water sport and as life saver. This device gives everybody the possibility to remain afloat for a long time and move rapidly over the surface of the water even if unable to swim. Another feature of my invention is to provide for a life saver apparatus in case, for instance, of shipwreck, because my device not only can be used as a life buoy, but also as a means to reach a relatively distant shore or a life boat. One other advantage of my device is that the motion required to actuate it is instinctive, so that even a child is able spontaneously to use it.

As a water sport game, the cyclic movement of the hands may be combined, if desired, with the motion of the legs in the crawl and my apparatus may also be used to learn more easily to swim.

Another advantage of my device is that it takes very little room when not in operation.

I attain these objects by the device illustrated in the accompanying drawings in which:

Fig. 1 is a section of the entire apparatus; and

Fig. 2 is an isometric view showing the shape of one float.

Referring to the drawings as an example of my water sport device, it is to be understood that various modifications may be made without changing the fundamental principle of the invention. For instance, the general shape of the float may be generally cylindrical with a sinuous periphery, the number of spurs may be inferior or superior to six.

My invention is essentially composed of a crankshaft 1 fitted with two handles 2 and 3 able to revolve freely around the crankpins 4 and 5 of the crankshaft. On the crankshaft 1 which can be made, for instance, of light metal tubing, are fastened four plates 6, 7, 8, and 9. A bag or float 10 is mounted between the plates 6 and 7 and solidly bonded to them and one other bag or float 11 is mounted between the plates 8 and 9 and also solidly bonded to them. The floats 10 and 11 are made of suitable flexible, air-tight and waterproof material such as rubber, rubberized fabric or flexible plastic, and are each provided with air valves 12 and 13 passing respectively through the plates 6 and 9. These valves permit inflation of the float with air, either with the mouth or in using a little hand pump. The air pressure shall be sufficient to secure the rigidity of the floats. The shape of the floats, when inflated, is shown in Fig. 2 and is like a cylinder

provided with a number of spurs 14. To increase the safety of the device, each float may be puncture proof in using a suitable product poured in it.

One other safety means which can be provided is to fasten to one handle a string which can be attached to the wrist of the swimmer, so that, in case of cramp or syncope, the body of the swimmer is always supported by the floats and does not sink or disappear under the water, thus facilitating a successful rescue.

The working of my water sport device is the following:

Lying face downward in the water, both arms and legs extended, the swimmer holds the handles and can easily maintain himself afloat, supported by the floats which are of such a volume that they are only half-way under water. When the swimmer wishes to move on the water, he actuates the crankshaft with his hands, forcing the floats to turn and to roll on the water. The floats which are provided with spurs push back the water and carry along the swimmer.

I claim:

1. A water sport and life-saving device, comprising in combination a pair of similarly shaped inflatable floats, each of said floats including spaced walls, the peripheries of which are of sinuous form, a cover of like configuration connecting said walls, and means rigidly connecting said floats in spaced apart relation, comprising a crankshaft having a pair of hand-grips rotatably mounted thereon.

2. A device of the character as set forth in claim 1 in which each of the walls of the inflatable floats has a reinforcing plate through which the crankshaft passes so as to maintain the shape of the floats and their positions on said crankshaft.

JEAN OLIVIER DE CHAPPEDELAINE.
